(57) **CLAIM**

The ornamental design for an article of jewelry, as shown and described.

DESCRIPTION

FIG. 1 is a perspective view of a first embodiment of an article of jewelry showing my new design.

FIG. 2 is a top view thereof.

FIG. 3 is a front view thereof, the rear view being a mirror image thereof.

FIG. 4 is a right side view thereof, the left side view being a mirror image thereof.

FIG. 5 is a perspective view of a second embodiment of an article of jewelry showing my new design.

FIG. 6 is a top view thereof.

FIG. 7 is a front view thereof, the rear view being a mirror image thereof.

FIG. 8 is a right side view thereof, the left side view being a mirror image thereof; and,

FIG. 9 is a perspective view thereof, showing the article of jewelry in a state of use.

The broken lines in the drawings represent portions of the article of jewelry and form no part of the claimed design. The other broken lines in FIG. 9 represent environmental subject matter only and form no part of the claimed design. The other broken lines in FIG. 9 represent environmental subject matter only and form no part of the claimed design.
